UNITED STATES PATENT OFFICE

1,988,471

CENTRIFUGAL PIPE CASTING APPARATUS

Paul L. Arnold, Edgewater Park, N. J., assignor
to United States Pipe and Foundry Company,
Burlington, N. J., a corporation of New Jersey

Application December 30, 1933, Serial No. 704,615

5 Claims. (Cl. 22—65)

My invention relates to a familiar type of centrifugal pipe casting apparatus in which a rotatable metallic mold extends through a water box and in which a portion of the mold lying within the water box is stayed or braced against lateral deflection by means of a surrounding bracing sleeve of greater internal diameter than the external diameter of the mold which it surrounds so as to provide for a flow of water through 5 said sleeve from and to the water box, the sleeve being provided with a multiple series of perforations through its wall to provide for a vertical circulation of water through the sleeve and over the surface of the mold during periods when the 10 mold is not in rotation. As heretofore constructed, trouble has occurred at times owing to an insufficient flow of water through the bracing sleeve and a prime object of my invention is to provide an improved construction which will insure at all times when the mold is in rotation an ample flow of water through the bracing sleeve and a satisfactory cooling of the mold. 15

In machines of the kind in question, a usual construction is one in which a driving sleeve is secured to one end of the mold, generally to the end of its bell section, the sleeve being spaced from the body of the mold over which it extends and extending through a wall of the water box with its free end in communication therewith 20 and in practice it has been found difficult to obtain a proper cooling of the portion of the mold over which the driving sleeve extends and in my co-pending application, filed December 30, 1933, Serial Number 704,614 I have described and 25 claimed an improved construction for securing an ample and determinable flow of water from and to the water box and over the portion of the mold lying within the driving sleeve. Essentially, this improvement consists in locating in the space between the driving sleeve and the mold a circular partition dividing these spaces into an inner and outer annular channel, connected together at their inner ends and in locating in the water box and in connection with the end of one 30 of said channels an annular centrifugal pump rotating with the mold and operative to bring about a continued flow of water through the annular channels formed between the circular partition and the mold and between the circular 35 partition and the driving sleeve. A further object of my present invention is to so locate and connect a centrifugal pump both with the bracing sleeve supporting the mid-section of the mold and with the channels formed in the spaces between the mold and the driving sleeve, that said centrifugal 40 pump will act to draw the water through the bracing sleeve and deliver it into one of the channels into which the space between the driving sleeve and the mold is divided so as to create a flow of water from the water box, first through the bracing sleeve and then through the channels formed between the driving sleeve and the mold and finally back to the water box. 45

It will be understood by those skilled in the art that the liability of the mold to lateral deflection depends mainly upon the length of the mold and its diameter and that a bracing sleeve is particularly useful in case of long molds of relatively small diameter. 50

As heretofore constructed, a bracing sleeve has been provided with a multiple series of holes or 55 perforations provided primarily to permit of a vertical flow of water through the sleeve and in contact with the mold when the mold is at rest but operative also during the rotation of the mold and sleeve to permit of an outward flow of water from the interior of the sleeve under the influence of the centrifugal force created by the rotation of the water with the sleeve, this centrifugal flow of the water through the perforations causing, 60 of course, an inflow of water through the open ends of the sleeve. My invention consists primarily in coupling to an open end of the perforated bracing sleeve an annular centrifugal pump of a diameter greater than that of the bracing 65 sleeve and otherwise so constructed that as it rotates with the mold and sleeve it will create a flow of water throughout the length of the sleeve of sufficient volume and velocity to insure the cooling of the mold to the desired degree, and a 70 further preferable feature consists in the coupling of a single annular centrifugal pump with the bracing sleeve and with one of the channels formed between the driving sleeve and the mold preferably with the inner channel formed in the 75 space between the driving sleeve and the mold so that the pump after drawing the water through the bracing sleeve will force it successively through the inner and outer annular conduits formed in the space between the driving sleeve and the mold and thence back to the water box. 80

While I have referred to the sleeve surrounding the mold as a bracing sleeve and while in 85 constructions as heretofore made it has served primarily this purpose, it is true that the perforated sleeve extending over the body of the mold, when connected with an annular centrifugal pump, performs an important function apart 90

from its usual function as a bracing sleeve and may be advantageously used in connection with molds of such diameter and such wall thickness as not to necessarily require bracing. Where the sleeve is not required to function as a bracing sleeve for the mold, it is obviously not necessary that it should revolve with the mold although, of course, the annular centrifugal pump must in all cases revolve with the mold.

10 My invention will be best understood as described in connection with the drawing in which

15 Figure 1 is an elevation of a portion of a centrifugal pipe casting machine to which my invention relates and embodying my improvements, the elevation being taken on a vertical plane passing through the center line of the pipe mold, the parts shown being broken away in the middle so as to enable the parts to be shown on a larger scale.

20 Figure 2 is a cross-sectional view taken on the line 2—2 of Fig. 1.

25 Figure 3 is a longitudinal sectional elevation showing the mold and bracing sleeve and embodying a modification of my invention; here also the central portion is broken away to permit the showing of the parts on a larger scale, and

30 Figure 4 is a fragmentary transverse section on the line 4—4 of Fig. 3.

35 A indicates the water box having end walls A¹ and A² and, as shown, a gear chamber A³ located at one end of the water box. B is a rotatable centrifugal mold having a bell end B¹, the mold extending through the water box with its ends projecting through the end walls A¹ and A², as shown. The bell end of the mold is provided with a separable ring flange indicated at B² and to this ring flange is secured a driving sleeve C which extends through the wall A² and into the water box and is so spaced from the bell end of the mold as to leave a water chamber between it and the mold in free communication with the water box; the portion of the driving sleeve extending into the gear chamber A³ is provided with gear teeth C¹ which are engaged by a train 40 of driving gears indicated at D and actuated by a motor D¹. As is shown, the spigot end of the mold is formed with a sleeve like extension B³ spaced away from the mold and extending through and forming a joint with the wall A¹ of the water box. E is a reinforcing sleeve extending around the central portion of the mold but spaced from it so as to leave a water chamber F between it and the mold and the mold is aligned with the sleeve by means of a multiple series of 45 set screws, as indicated at G, a multiple series of set screws, as indicated at G, a multiple series of perforations as indicated at E¹ are formed along the length of the reinforcing sleeve E.

50 To the extent above described the construction indicated is not new with me and represents constructions which have been in use in centrifugal pipe casting machines for many years past.

55 Referring next to Fig. 1, which illustrates a construction embodying the main feature of my invention, H represents an annular rotary plate rotating with but not directly secured to the mold at some distance from the end of the bracing sleeve and extending outward so that its outer portion faces an annular rotary extending plate J secured to the end of the bracing sleeve and between the opposing faces of these plates are secured a series of impeller blades K, so arranged 60 as to constitute with the plates a centrifugal pump indicated at O. As shown in Fig. 1, the centrifugal pump is connected to the bracing

65 sleeve at its end lying close to the spigot end of the mold and in Fig. 3 the centrifugal pump constructed in substantially the same manner is connected to the end of the bracing sleeve which lies adjacent to the bell end of the mold. In the construction of Fig. 3, I have indicated the space lying between the driving sleeve C and the mold as divided into two annular channels connected at their inner ends, by a circular partition L, the channels being indicated at M and M¹ and the 70 connection between them at M² and I have indicated a hood extension from the outer end of the circular partition as indicated at N, which extends over the centrifugal pump O¹ a flange N¹ at the end of the hood lapping but not being attached to the radial plate J. The hood forming a delivery channel, as indicated at P, by means of which water delivered by the pump is forced into the annular channel M, thence through the connection M² into the outer channel M¹ and 75 thence back into the water box. To check such rotary movement as may be imparted to the water in passing through the annular centrifugal pump, I provide vanes as indicated at Q in the channel P. The above described construction, leaving out of consideration the connection of the centrifugal pump with a bracing sleeve, forms in part the subject matter of my co-pending application filed December 30, 1933 Serial Number 704,614.

80 In operation and referring first to Fig. 1, when the mold is in rotation the centrifugal pump O revolves with it and at a linear speed determined by its radial distance from the center of the revolving mold and its operation is to draw the water from the water box into the open end of the bracing sleeve through the space F between the sleeve and the mold and thence radially outward into the water box. The capacity of the centrifugal pump is determined partly by its linear speed and partly by the setting of the impeller blades and should be such as to insure that water is drawn through the bracing sleeve in sufficient quantity and at sufficient velocity to bring about 85 such cooling of the mold as is found to be desirable in use. The important function of the multiple perforations formed in the bracing sleeve E is to insure that during rest periods, when the mold is not in rotation, a flow of water will still occur through the sleeve and in contact with the mold in a vertical direction. When the mold and sleeve are in rotation, the water passing through the sleeve is also rotated and has, therefore, a tendency to flow outward through the perforations formed in the sleeve, a tendency which will be more or less counteracted by the action of the 90 centrifugal pump which must be such as to insure the maintenance of a flowing stream of water within the bracing sleeve and in contact with the mold during the casting and so long as the mold remains at a normal rotative speed.

95 Referring next to Fig. 3, the operation of the centrifugal pump, here indicated at O¹, with regard to the bracing sleeve, is the same as that described in connection with Fig. 1, but in place of delivering the water drawn from the sleeve directly into the water box, as is the case with the construction of Fig. 1, the water delivered from the annular centrifugal pump O¹ passes through the conduit P formed by the hood N, into the annular conduit M formed between the circular partition and the bell end of the mold, thence through the passage M² and annular channel M¹ into the water box.

Having now described my invention, what I claim as new and desire to secure by Letters Patent, is:

1. In a centrifugal pipe casting machine comprising a water box, a metallic mold extending through said water box, means for rotating said mold, the combination therewith of a sleeve surrounding but spaced away from the mold, said sleeve having an open end for the inflow of water and an outlet opening located at a distance from said inlet opening and having perforations formed through its walls between said inlet and outlet openings and an annular centrifugal pump rotating with the mold and connected to draw water in through the inlet opening and out through the outlet opening of the sleeve so as to secure a longitudinal flow of water through the sleeve between said inlet and outlet openings. 15
2. In a centrifugal pipe casting machine comprising a water box, a metallic mold extending through said water box, means for rotating said mold and a perforated sleeve surrounding and spaced away from the central portion of the mold said sleeve having open ends at both extremities, improved means for providing for a proper flow of water between the sleeve and the mold which consists in combining with one of the open ends of the sleeve an annular centrifugal pump of greater diameter than the sleeve and rotatable 20 with the mold and operative to draw water through the sleeve and discharge it into the water box.
3. In a centrifugal pipe casting apparatus comprising a water box, a rotatable metallic mold extending through said water box and having attached at one end a driving sleeve extending over but spaced away from the adjacent portion of the mold so as to leave an annular chamber between it and the mold, said driving sleeve extending 25 through the wall of the water box and opening at its free end into the water box and said rotatable mold having its portion extending through the water box provided with a perforated sleeve surrounding but spaced away from the mold, improved means for creating a flow of water through the sleeve and through the spaces between the driving sleeve and the mold which consists in providing at the end of the sleeve surrounding the central portion of the mold adjacent 30 to the driving sleeve an annular outwardly extending conduit chamber provided with impeller blades and constituting therewith a centrifugal pump, in further securing in the space between the driving sleeve and the mold a circular partition dividing said space into inner and outer passages connected together at their inner ends and in providing an annular conduit connecting the 35 delivery side of the centrifugal pump with the outer end of the annular passage formed between the circular partition and the mold. 40

tion dividing said space into inner and outer passages connected together at their inner ends and in providing an annular conduit connecting the delivery side of the centrifugal pump with the outer end of the annular passage formed between the circular partition and the mold. 5

4. In a centrifugal pipe casting machine comprising a water box, a metallic mold extending through said water box, means for rotating said mold and means for bracing the mold against lateral deflection, consisting of an annular perforated sleeve surrounding the central portion of the mold but spaced away therefrom so as to leave a water channel between the mold and the sleeve and means supported by the sleeve said sleeve having open ends at both extremities for aligning the mold therewith, improved means for providing for a proper flow of water between the sleeve and the mold which consists in combining with one of the open ends of the sleeve an annular centrifugal pump of greater diameter than the sleeve and rotatable therewith and operative to draw water through the sleeve and discharge it into the water box. 15

5. In a centrifugal pipe casting apparatus comprising a water box, a rotatable metallic mold extending through said water box and having attached at one end a driving sleeve extending over but spaced away from the adjacent portion of the mold so as to leave an annular chamber between it and the mold, said driving sleeve extending through the wall of the water box and opening at its free end into the water box and said rotatable mold having its portion extending through the water box provided with a perforated bracing sleeve surrounding but spaced away from the mold and provided with means supported by the sleeve for aligning the mold, improved means for creating a flow of water through the bracing sleeve and through the spaces between the driving sleeve and the mold which consists in providing at the end of the bracing sleeve adjacent to the driving sleeve an annular outwardly extending conduit chamber provided with impeller blades and constituting therewith a centrifugal pump, in further securing in the space between the driving sleeve and the mold a circular partition dividing said space into inner and outer passages connected together at their inner ends and in providing an annular conduit connecting the delivery side of the centrifugal pump with the outer end of the annular passage formed between the circular partition and the mold. 45

PAUL L. ARNOLD.
